MAUDE T. KELLEY, OF MOUNT VERNON, NEW YORK, ASSIGNOR OF ONE-FOURTH TO
BRATSON CORPORATION, OF MOUNT VERNON, NEW YORK, A CORPORATION OF NEW
YORK

CLOTHES WASHER

Application filed February 12, 1931. Serial No. 515,291.

This invention relates to clothes washing devices and in particular manually operable plungers.

It is the object of my invention to provide a simple and inexpensive vacuum cup clothes plunger or paster, constructed so as to produce an efficient cleansing action with a minimum of muscular effort and without any harmful results to the articles being washed.

With these and other objects in view, the invention consists in the novel construction, arrangement and combination of parts, hereinafter described, illustrated in some of its embodiments in the accompanying drawing and particularly pointed out in the appended claims.

In the drawing, Figure 1 is a side elevational view of my improved clothes plunger, Figure 2 is a plan view of the top of the suction cup, Figure 3 is a plan view partly in section of the underside of the suction cup and Figure 4 is a plan view partly in section of the underside of a modified form of suction cup.

My improved clothes washing device comprehends the provision of a plunger or paster 1, having a handle 2, the upper end of which is formed with spaced enlarged portions 3 and 4, providing a grip fashioned to accommodate the hand of the operator. The enlarged portions 3 and 4 cooperate to prevent the plunger from slipping from the grasp of the operator and at the same time permit it to be held with a lighter grip than ordinarily would be required.

A suction cup 5 is carried on the lower end of the handle 2 and is removably secured thereto by means of the upstanding neck 6 which receives and frictionally engages the end of handle. A series of apertures 7, are provided in the upper face of the suction cup through which the cleaning fluid may be expelled from and sucked into the interior of the cup 5. A guard plate 8 is carried by the handle 2 above the suction cup 5, so that the liquid expelled through the apertures 7 does not escape from the vessel in which the washing operation is performed.

The interior of the suction cup 5 is provided with a plurality of vertically disposed

walls 9, which divide the cup into a number of cells or cavities 10, which are circumferentially disposed around the central cavity 11. The lower edge 12, of the wall of the central cavity 11, terminates a short distance below the rim 13 of the shell of the cup, so that the lower edges of the cup and the dividing walls 9 lie within the surface of a cone which arrangement facilitates the distribution of the clothes being washed and tends to arrange them evenly over the face of the suction cup.

The central cavity 11 is provided with lateral ports 14, communicating with the cavities 10, which are arranged thereabout so that the cleansing fluid is free to circulate from one cell to the other of the cup. By arranging the suction cup with a plurality of cells as shown, the articles being washed are prevented from wedging and jamming into the cup and thus stopping the free flow of the washing fluid through the apertures 7. This is an important feature of my device and will be better appreciated after considering the operation of the plunger which will be described in detail presently.

In the modified form of cup shown in Figure 4, lateral apertures 15 are provided for the escape of the washing fluid, in place of the aperture 7 shown in connection with the previously described form of suction cup. By arranging the cell apertures in the side of the suction cup the shield 8 may be dispensed with. In either case, however, the device will operate satisfactorily without the shield, which is provided to prevent splashing and escape of washing fluid when the device is in the hands of a careless or inexperienced operator.

The handle 2 may be made of wood though not necessarily so. The disk 8 is fashioned from a light noncorroding metal stamping. Other materials than those mentioned may be used in making the disk, though it has been found that aluminum is a highly satisfactory material for such purposes. The suction cup 5 in its preferred form, is made of molded rubber of a composition highly resistant to the action of soap solutions, naptha, carbon tetrachloride and other liq-

uids commonly used for cleaning purposes, and it has the physical characteristics of the rubber used in automobile tires, being slightly deformable under slight stresses but of sufficient rigidity to substantially retain its shape in normal use.

In the operation of the device the articles to be cleaned are placed in a suitable vessel containing the cleansing fluid which may be a mixture of soap and water or a dry cleaning liquid. The plunger is then gently reciprocated with an easy motion with the suction cup at or near the top of the liquid level and is shifted from place to place so as to bring all the clothes in the vessel under the cleansing action of the device.

It has been observed in the operation of my improved washer that during the reciprocation of the plunger the clothes adhering to the suction cup tend to distribute themselves evenly over the face thereof by reason of the conical outline of the underside of the cup. At the same time the cleansing fluid may be observed to escape from the apertures 7 or 15 on the downward stroke of the plunger showing that the liquid is forced through the clothes engaging the underside of the cup, thus providing an ideal mode of washing silks and other fine articles fashioned from delicate materials which are easily ruined by the rubbing and violent agitation produced by other modes of washing.

The openings 7 are of such size that when the plunger is operated below the surface of the cleaning fluid, the articles being washed tend to adhere to the face of the plunger on its upward stroke until sufficient liquid has entered the cup by way of the openings 7 to displace the clothes from this position.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims.

Having thus described my invention what I claim is:

1. In a clothes washing device, an integrally formed waterproof non-metallic cup of molded construction, a handle receiving portion formed thereon, and a plurality of relatively thin inter-connected vertical walls within said cup dividing the same into a number of open cells, there being holes communicating with said cells to permit restricted fluid flow therethrough, the lower edges of said walls sloping downwardly and inwardly toward the center of said cup whereby in the operation of the device the exposed edges of said walls tend to spread and distribute the clothes evenly over the face of the cup

and at the same time prevent their entrance into the cup.

2. In a clothes washing device, a plunger comprising a rubber suction cup, a handle receiving portion formed therein, radially arranged relatively thin walls integrally formed with said cup for dividing its interior into a plurality of separate cavities, the lower edges of said walls sloping downwardly and inwardly from the rim of said cup so as to form a grid-like guard over the mouth of the cup to distribute the clothes being washed radially outwardly and evenly across the mouth of said cup and at the same time to prevent their entering into said cup, the wall of said cup having holes communicating with said cavities to permit restricted flow of washing fluid back and forth through said cup.

In testimony whereof I affix my signature. 85
MAUDE T. KELLEY.
